UNITED STATES PATENT OFFICE.

JOHN W. SIBBALD, OF NEW YORK, N. Y.

GOLF TEE.

1,413,496.

Specification of Letters Patent. Patented Apr. 18, 1922.

Application filed May 28, 1921. Serial No. 471,543.

To all whom it may concern:

Be it known that I, JOHN W. SIBBALD, a subject of the King of Great Britain, and a resident of New York, in the county of New York and State of New York, have invented certain new and useful Improvements in Golf Tees, of which the following is a specification.

The invention relates to an improved golf ball tee which a player may conveniently carry with him and by which he may adjust the height of the ball to suit the requirements. The invention has for its object to provide a device of this character which shall be light and readily portable and wherein the adjustable holder will be so constructed that it may not be detached from the base of the tee and, therefore, cannot be lost. A still further object of the invention, consists in the provision of means whereby the adjustable portion will be self-cleaning and thereby prevent same from sticking or becoming clogged with dirt or other foreign material.

25 The nature of the invention, however, will best be understood when described in connection with the accompanying drawings; in which—

Fig. 1 is a plan view of the improved tee. 30 Fig. 2 is a vertical section taken therethrough on the line 2—2, Fig. 1.

Figs. 3 and 4, are detail views of the adjustable ball support, Fig. 3 being a plan thereof, and Fig. 4 an elevation.

35 Similar characters of reference designate corresponding parts throughout the several views.

Referring to the drawings, 10 designates a circular skeleton base, preferably, from a portion of which a segment has been removed leaving a clearance space 11; and it is also preferred to bevel the edge of the material at this clearance space so that in case a club should strike the base, the blow 45 would tend to be deflected upwardly. At the central portion of the base, there is provided a conical hollow boss 12, which is provided with internal threads 13; and there is designed to fit said conical boss a ball support member 14. At its lower end, the member 14 is provided with a number of threads 15 adapted to engage the threaded portion of the boss 13 and thereby to be adjustable vertically thereof.

55 In order to prevent withdrawal and possible loss of the said ball holding member,

the upper outer end 16 of same is upset or turned slightly over (as shown) so that the member 14 may not be withdrawn through the boss in the one direction. To prevent its withdrawal in the other direction, the upper edge of the boss is provided with an inwardly directed shoulder 17 to form an abutment for the threads 15 and thus prevent withdrawal of the ball holder in the opposite direction.

Moreover, I have found by providing longitudinal slots 18 in the periphery of the ball holder, that any dirt or foreign matter which might accumulate in the boss will be readily removed in the rotation of said member through the action of the sharp edges of the grooves.

The outer end of the member 14, moreover, is provided with a semi-spherical recess or cavity 19 to retain a ball (not shown); and the height of same above the ground may be adjusted to suit by rotating the member 14 accordingly.

I claim:—

1. A golf ball tee, comprising a base support having a central protruding boss and a recessed member mounted in said boss and adapted to receive the golf ball and adjustable in the boss.

2. A golf ball tee, comprising a skeleton base support having a central protruding boss and a recessed member mounted in said boss and adapted to receive the golf ball and adjustable in the boss.

3. A golf ball tee, comprising a circular base support having a segmental portion removed and provided with a central protruding boss and a recessed member mounted in said boss and adapted to receive the golf ball and adjustable in the boss.

4. A golf ball tee, comprising a circular base support having a segmental portion removed with the edge thereof bevelled, said support having a central protruding boss 100 and a recessed member mounted in said boss and adapted to receive the golf ball and adjustable in the boss.

5. A golf tee, comprising a base support and a recessed member rotatably mounted 105 therein to afford an adjustment of same relatively to the support and having means to engage the said support to prevent removal therefrom.

6. A golf ball tee, comprising a base provided with a hollow protruding boss internally threaded, and a ball support threaded

to fit said boss, rotatable therein and having its upper edge turned over to prevent removal therefrom in one direction and the edge of the boss being turned inwardly to prevent removal of said ball support in the other direction.

7. A golf tee, comprising a threaded base support and a threaded recessed member to rotate therein, said member having longitudinal grooves in its periphery.

8. A golf ball tee, comprising a circular skeleton base having a portion removed to provide a clearance space and the edge at the removed portion being bevelled, said support being provided with a hollow conical boss and internally threaded, a ball sup-

port having threads to fit said conical boss and provided with a recess at its outer end to receive a ball, said ball support having its outer edge turned over to prevent removal from the conical support in one direction and the outer edge of the boss being turned inwardly to engage the threads of said ball support and prevent its removal in the other direction and the said ball support having its periphery grooved longitudinally to assist in the removal of foreign material from said threads.

Signed at New York, in the county of New York and State of New York, this 20th day of May, A. D. 1921.

JOHN W. SIBBALD
